Inventor:

Herbert H. Rosenthal,
By his Attorney, Leo McNeath

UNITED STATES PATENT OFFICE.

HERBERT H. ROSENTHAL, OF PITTSBURGH, PENNSYLVANIA.

LINING FOR HEAD COVERINGS.

Application filed November 4, 1922. Serial No. 599,018.

To all whom it may concern:

Be it known that I, HERBERT H. ROSENTHAL, a citizen of the United States, and a resident of Pittsburgh, Allegheny County, State of Pennsylvania, have invented a new and useful Improvement in Linings for Head Coverings, of which the following is a specification sufficient to enable those skilled in the art to which the invention applies to utilize the same.

My improvement relates to the linings of head-coverings, generally such as hats, caps, bonnets, and other forms of head-gear; and my object is to afford simple, convenient, and practicable means whereby the finished articles, to which my improved linings are applied, may be tagged by the wholesale or retail dealer without danger of injury or impairment of the lining when the tag is detached by the purchaser, or otherwise. Heretofore, it has been customary for the wholesale or retail dealer to sew or otherwise attach the purchase tag directly to the lining, so that the detachment thereof after sale was difficult, if not detrimental or injurious to the lining, resulting frequently in the tearing or distortion thereof. This difficulty I obviate by my invention, which consists essentially in forming the lining with a permanent loop integral therewith, to which the tag cord may be detachably secured, substantially in the manner and for the purpose herein set forth.

In the accompanying drawings,
35 Fig. 1, is a perspective view of a crown lining formed with my tag loop, and exemplifying the use thereof;
Fig. 2, is a view of the inner side thereof; and
40 Fig. 3, is a sectional detail illustrating the incorporation of my tag loop with the crown lining.

The crown lining, so called, shown in the drawings, consists of the ordinary crown section *c*, and the side section *c'*, sewed thereto in the usual manner. My tag loop *c²*, 45 may be permanently secured to the lining by any suitable means, as by incorporating the ends of the loop *c²*, in the seam *s*, between crown and side sections *c*, *c'*, of the 50 lining, as indicated particularly in Fig. 3, of the drawings,—it being understood that I do not limit and restrict myself in this respect, nor to the specific form of lining shown herein,—the lining, in a unitary sense, 55 being made and shaped in accordance with requirements in ways well known in the prior state of the art.

The tag *T*, is provided with the usual attachment cord *a*, which, in applying to the 60 lining, is passed through the loop *c²*, a sufficient distance to permit of the insertion of the tag *T*, through the bight of the cord thus formed; or the cord *a*, may be secured to the loop *c²*, of the lining by tying or otherwise, as may be found most convenient or expedient in practice; the gist of the invention being the provision of the loop *c²*, integral with the lining as a means for effecting the temporary attachment of the tag *T*, 70 by means of its cord *a*, substantially as indicated in Fig. 1, of the drawings.

What I claim as my invention and desire to secure by Letters Patent is,

A hat lining comprising a crown section 75 and a side section, and a tag loop permanently secured to and between the said sections at the junction thereof, in close proximity to the lining and normally substantially parallel therewith.

HERBERT H. ROSENTHAL.
